(57) **CLAIM**

The ornamental design for an electrical cabinet slot cover, as shown and described.

DESCRIPTION

FIG. 1 is a top, front perspective view of an electrical cabinet slot cover arranged in an electrical cabinet, showing our new design.

FIG. 2 is a top, front perspective view of the electrical cabinet slot cover of FIG. 1.

FIG. 3 is a bottom, rear perspective view of the electrical cabinet slot cover of FIG. 1.

FIG. 4 is a rear view of the electrical cabinet slot cover of FIG. 1.

FIG. 5 is a front view of the electrical cabinet slot cover of FIG. 1.

FIG. 6 is a right side view of the electrical cabinet slot cover of FIG. 1.

FIG. 7 is a left side view of the electrical cabinet slot cover of FIG. 1.

FIG. 8 is a bottom view of the electrical cabinet slot cover of FIG. 1; and,

FIG. 9 is a top view of the electrical cabinet slot cover of FIG. 1.

The broken lines in the figures illustrate portions of the electrical cabinet slot cover that form no part of the claimed design.
